CHRISTMAS TREE BOARD

Reuben F. Kidwell, Atlanta, Ga.

Application May 23, 1934, Serial No. 727,099

10 Claims. (Cl. 46—37)

This invention relates to decorative devices, and more particularly, to a new and improved Christmas tree board.

During the Christmas season, in most of the 5 civilized countries of the world the custom exists of cutting down a living tree of suitable size and bringing such into the house, where said tree is decorated with ornaments of various kinds, tinsel, multi-colored lights, et cetera. Trees suitable for this purpose include the evergreen, various varieties of fir, pine, and spruce; and when utilized in the foregoing manner are commonly called "Christmas trees."

In order to maintain such trees upright in the 15 room where they are placed, a supporting stand or holder is usually affixed to the trunk and base of the tree, such holders comprising a plurality of arms extending at right angles to the base and forming a cross-shaped member.

It is likewise customary to provide decorations 20 around the foot of and beneath the tree, but this detail has been left largely to chance, and in most cases represents a haphazard and unsystematic proposition, such decorations being moved about at will, and usually embodying little real beauty.

Further, since there is usually a constant dropping of withered leaves and twigs and other matter from the Christmas tree, it is important that 30 some means be provided to catch such before they are deleterious to the premises, as when ground into the floor or floor covering, or tracked into other parts of the house.

An object of the present invention is to provide 35 a decorative board for association with a Christmas tree, said board having both utilitarian and aesthetic advantages.

A further object is to provide such a board 40 that may be dispensed in a semi-completed form, which enables the purchaser to exercise his own ingenuity and taste in completing the artistic conception desired to be embodied in the finished assembly.

Another object is to provide a board of the foregoing type that can be taken down each year and 45 put up the next, in a different arrangement if desired, thus relieving the monotony of having the same decorations each Christmas, yet providing an economical decoration in that it may be used many times.

50 A still further object is to provide a device that will catch the droppings from a Christmas tree, and thus prevent such from being ground into the carpet or floor of a room, as often happens in the case of the conventional tree.

55 These and other objects made apparent

throughout the further progress of this specification are accomplished by means of my Christmas tree board, a full and complete understanding of which is made possible by reference to the drawing herein, in which:

Fig. 1 is a view in perspective of my device in semi-complete form, associated with a Christmas tree; the various stages of assembly being clearly indicated by reading the drawing from left to right.

Fig. 2 is an enlarged top plan view of one of the decorative strips dispensed with my device, said strip simulating a hedge.

Fig. 3 is an end view of the strip illustrated in Fig. 2.

Fig. 4 is a top plan view of another of the decorative strips distributed with my device, said strip representing a brick wall.

Fig. 5 is a top plan view of still another decorative strip dispensed with my device, said strip representing a stone wall; the strips illustrated in Figs. 4 and 5 being similar in vertical cross-section to the strip shown in Fig. 2.

Like numerals refer to corresponding parts throughout the figures of the drawing.

Referring now to the drawing, Fig. 1, my invention consists of a board 10, preferably rectangular in shape, and of a size contemplated to extend beyond the edges of the lower spread of a tree 11 with which it is associated. Board 10 may be cut from heavy cardboard, or other suitable material, such as, for instance, any of the well known insulating boards now on the market; and is provided with a cut-out space 12 in its center to receive the arms of a stand 13, said cut-out portion as shown being in the form of a cross, in keeping with the Christmas motif. If desired, the edges of 10 may be reinforced as by brading or otherwise attaching a narrow wooden strip 14 beneath the outer edges thereof, which strips may also be extended cross-ways under the board if further strength is wanted.

In order that board 10 may be raised from the floor to permit passage of electric light cords thereunder, for purposes explained in detail elsewhere herein, said board is provided at its corners and elsewhere as desired, with blocks 15, which blocks may be square in shape, composed of wood, and of a thickness sufficient to raise 10 slightly off the floor of the room in which it is placed. Small brads or glue have been found efficacious in uniting corners 15 with strips 14 and the board proper.

Strips 16 of cardboard, wood, or other suitable material of a selected width and thickness and

110

provided with a rough finish, and colored green to resemble a hedge, are permanently attached to the outside edges of 10; while the edges of cross 12 may be likewise ornamented. Board 10 may 5 be cut into two identical sections along line 17 (Fig. 1), and joined when in operative position as by passing two or more short strips of cardboard at right angles to line 17 and securely anchoring the ends of such strips with thumb-tacks.

A series of holes or perforations 18 may be provided at intervals in board 10; and the upper face of said board may be ruled with guide lines such as 19 and 19a, the purpose of which apertures and lines is made clear during the further progress of this specification.

I provide a series of strips 20 (Figs. 2 and 3), to be dispensed with the board described heretofore, said strips being fabricated of cardboard 20 and/or other selected materials, and having an upper portion 21 of greater thickness but less width than the lower portion 22, which is preferably thin enough to permit the passage of a thumb-tack there-through without difficulty. 25 The outer edges of 21 may be provided with a rough surface such as 21a, and colored green to resemble a hedge.

Strips similar to 20 may be appropriately marked to simulate other decorative elements, 30 as, for instance, the brick wall 20a illustrated in Fig. 4, the upper portion of which strip is colored red; and the stone wall 20b shown in Fig. 5, the upper portion of which strip is gray in color. Other artistic conceptions to be embodied in or 35 upon strips of the general type of 20 will suggest themselves to those who are artistically inclined.

Strips 20 may be cut into uniform short lengths to be sold with the set, or they may be distributed 40 in rather long sections, the party who sets up the board then cutting from these strips lengths suitable for the various elements of the design to be worked out.

In operation my device works as follows: The 45 sections of board 10 are united as previously described herein (assuming that the board has been divided into more than one piece), the sections being assembled around the Christmas tree stand which, with the tree, has been previously 50 set up. A plan of construction is then decided upon, the elaborateness of which may extend from a small group of houses with adjuncts, to a complete village depending upon the amount of material available and the wishes of the builder. 55 The ground-work for the project is then laid by forming from proper sections of strips 20 the necessary hedges, walls, streets and the like, it being only necessary to select or cut the strip indicated by the plan, and then fasten such in 60 place on the board by means of thumb-tacks. For instance, in the section indicated at "B" of Fig. 1, the setting for a house has been laid, hedge strips 20 being held in place by thumb-tacks 23, providing picturesque surroundings for 65 a miniature dwelling. In section "C" of the figure, a house 24 has been installed in a like setting, this portion of the drawing illustrating a completed area of the board. Imitation snow, green saw-dust, or sand may be sprinkled over 70 the bottom portions 22 and thumb-tacks 23 of the strips to conceal said portions and provide a finished appearance to the whole.

It is not intended that houses such as 24 shall necessarily be sold as a part of the instant 75 Christmas tree board, miniature dwellings of this

type, or other desired structures, being easy of procurement, particularly at department stores during the Christmas season.

The windows of house 24 are preferably transparent, and within the structure is placed an electric light bulb supplied with current from a cord passed through an aperture such as 18. The cord supplying current to the Christmas tree proper may be passed under board 10, out through opening 12, and hence to the tree.

Section "A" of Fig. 1, is representative of the board in its incomplete state, ready, however, to be assembled as described.

Guide lines 19 and 19a, which are drawn on the square, are provided to furnish a straight edge for building and lining up the houses, hedges, walls and other elements upon the board, their presence facilitating accurate construction without extensive additional mathematical computation.

When completely assembled, my Christmas tree board presents a beautiful and inspiring sight, and adds tremendously to the effectiveness of the Christmas decorations. Adults and children may spend many delightful hours in planning and constructing the Christmas village; and each year the 100 plan may be a new one. In addition, the device performs a useful function in catching whatever may drop from the tree during the holiday season, thus conserving the permanent household. It is likewise apparent that my device is a simple, 105 economical, and practical one, and that it represents a unique contribution to the decorative arts.

While I have described in detail herein a preferred form of my invention, it is to be noted that certain modifications, changes, additions and 110 omissions may be resorted to, particularly in regard to strips 20, without departing from the scope of the invention as defined by the appended claims.

I claim:

1. A device of the class described, comprising a rectangular board of suitable dimensions, a central opening in said board, a raised decorative border around the upper edge of said opening, a series of smaller apertures in said board, a raised decorative border around the outside of said board, said border being colored to simulate a hedge; reinforcing strips around the lower outside edges of said board, means spacing said board from the floor of a room in which it is placed, 120 guide lines on the face of the board, and detachable strips fastened to the upper surface of said board, said strips simulating hedges, brick walls, stone walls, and the like.

2. A device of the class described comprising a rectangular board of suitable dimensions, a central opening in said board, a raised decorative border around the upper edges of said opening, a series of smaller openings in said board, a raised decorative border around the outside edges of 130 said board, reinforcing strips around the lower outside edges of the board, means spacing said board from the floor of a room, and detachable strips fastened to the upper plane surface of said board in such a manner as to simulate hedges, 135 walls, and the like.

3. A Christmas tree board comprising a board of suitable dimensions, a central opening in said board, a raised decorative border around the upper edge of said opening, a series of smaller apertures in said board, means spacing said board from the floor of a room, and detachable strips fastened to the upper plane surface of said board, 145 said strips simulating hedges, walls, and the like.

4. A device of the class described comprising a 150

- thin board presenting a plane surface of greater dimensions than the lower spread of a tree with which the board is contemplated to be associated, a central opening in said board to receive a stand, a series of smaller openings in said board, a raised decorative border around the outside edges of said board, means spacing the board from the floor of a room, and detachable strips fastened to the upper plane surface of said board, said strips simulating hedges and the like. 5
5. A device of the class described comprising a thin board having a plane surface of greater extent than the lower spread of a tree with which the device is intended to be associated, a central opening in said board, a series of smaller openings in the board between said central opening and the edges of the board, means to space the board from the floor of a room in which it is placed, and detachable strips fastened to the upper surface of 15 said board, said strips simulating details of landscape.
6. A Christmas tree board comprising a thin board having a plane surface of considerably greater extent than the lower spread of a tree with which the device is associated, a central opening in said board, a raised decorative border around the edges of said opening, a raised decorative border around the upper outside edges of said board, and detachable strips fastened to the 25 upper surface of the board, said strips simulating architectural details.
7. A Christmas tree board comprising a thin board having a plane surface of greater extent than the spread of a tree with which the device is associated, a series of openings in said board, 30
- a raised decorative border around the outside edges of the board, means spacing said board from the floor of a room, and detachable strips fastened to the upper plane surface of said board, said strips simulating hedges and the like. 80
8. A Christmas tree board comprising a thin board of suitable dimensions, a central opening in said board, a raised decorative border around the upper edges of said opening, reinforcing strips around the lower outside edges of said board, means spacing the board from the floor of a room in which it is situated, and detachable strips fastened to the upper plane surface of said board, said strips simulating hedges, walls, and the like. 85
9. A Christmas tree board comprising a thin board of suitable dimensions, a central opening in said board, a series of smaller openings disposed about said central opening, a raised decorative border around the upper outside edges of the board, means spacing the board from the floor of a room, guide lines on the face of the board, and detachable decorative strips fastened to the upper surface of the board, said strips simulating details of landscape and architecture. 90
10. A Christmas tree board comprising a thin board of suitable dimensions, a central opening in said board, a series of smaller openings disposed about said central opening, a raised decorative border around the upper outside edges of the board, means spacing the board from the floor of a room, and detachable decorative strips anchored to the upper face of the board, said strips simulating details of architecture and landscape. 100 105
